UNITED STATES PATENT OFFICE.

GEORGE AUGUST MUENZENMAIER, OF LEBANON, OHIO, ASSIGNOR TO THE PETERS CARTRIDGE COMPANY, OF CINCINNATI, OHIO, A CORPORATION OF OHIO.

SHELL.

932,562.

Specification of Letters Patent. Patented Aug. 31, 1909.

Application filed August 26, 1907. Serial No. 390,111.

To all whom it may concern:

Be it known that I, GEORGE AUGUST MUENZENMAIER, a citizen of the United States, residing at Lebanon, in the county of Warren and State of Ohio, have invented certain new and useful Improvements in Shells, of which the following is a full, clear, and exact specification.

The invention relates to improvements in the construction of shells for use in firing powder and relates more particularly to that type of shells in which there is provided an anvil against which the fulminate is driven by the firing pin, the same being set in the battery cup lengthwise, and having its upper extremity projecting into a primer cup containing the fulminate. The entire battery primer being covered with an imperforate hood of ductile material forming a gas proof covering, the forward edges of which are reamed outwardly and firmly embedded in the paper wad or base in the interior of the shell.

The primary object of the present invention is to simplify the construction of the anvil against which the fulminate is driven and to make the same more effective in firing the charge.

A further object of the invention is to simplify the construction of the ordinary battery primer, thereby improving its efficiency.

To the attainment of these ends and the accomplishment of other new and useful objects, as will appear, the invention consists in the features of novelty in the construction, combination and arrangement of the several parts hereinafter more fully described and claimed, and shown in the accompanying drawings illustrating an exemplification of this invention, and in which—

Figure 1 is a vertical sectional view of the butt of a shot gun shell embodying the invention, and Fig. 2 is a sectional view of the same taken on the line 2—2 of Fig. 1, looking in the direction indicated by the arrows, Figs. 3, 4, and 5 are vertical sectional views of the various parts of the hooded primer, while Figs. 6, 7, and 8 are top or bottom plan views of the same looking into their open ends or interiors.

In the drawings 1 designates a metal cup or butt, 2 the paper shell and 3 the interior

paper base, which are all of the ordinary forms as particularly used in shot gun shells for nitro powder, the shell being of the central fire type with a hole through the center of cup 1 and base 3 for the insertion of the primer.

4 is the interior shell called the "primer cup," which contains the fulminate 5, and has the anvil 6^a projecting upwardly into the interior thereof adjacent the fulminate 5, as shown in the assembled view, Fig. 1. The part 6 is a cup usually designated as the "battery cup," but is not of the ordinary construction in that the anvil as indicated at 6^a is constructed integrally therewith and protrudes upwardly into the interior of this cup as clearly shown in Figs. 5 and 8, and also in the assembled view Fig. 1. It will be noted that the anvil 6^a does not comprise a strip of sufficient width to cover the entire bottom of the cup 6, but is comparatively narrow so that on either side thereof appear vents 7. The upper edge is provided with an outwardly turned flange 6^b. The primer cup, with the fulminate 5 at the closed end thereof and usually covered with a tin foil, or other water-proof covering, as indicated at 8, is inserted in the battery cup and pressed downwardly until the primer cup rests on the bottom of the battery cup or thereabout, as illustrated in Fig. 1, with the top of the anvil 6^a adjacent the fulminate. The battery cup primer thus formed is now placed inside a third, and exterior, cup or hood 9 which, in this step of the operation of assembling, is usually a thin metallic shell with straight sides having an internal diameter in excess of the external diameter of the flange 6^b of the battery cup and extending beyond its length. The shell or hood 9 is then compressed about the flange 6^b and tightened about the sides of the battery cup 6. By another operation it is forced as a whole through the opening in cup 1 and base 3, the flange of the hood, as at 9^b, resting within the depression provided for it in the exterior surface of the base, and upon the flange of the base there formed, as indicated at 9^a. The inner edges 9^a of the hood 9 extending through and beyond the base 3 are turned back, upset, or outwardly crimped as at 9^c,

and embedded in the paper base or, in the particular form of shell shown, in what is called wound wad 3.

By this construction it will be seen that 5 the primer cup rests on the bottom or nearly so of the battery cup with which it is forced into contact as described, and the anvil 6^a being firmly and centrally set as contradistinguished from the ordinary form of separating anvil, the firing of the primer is rendered more certain and effective. It will also be seen that this construction is much more economical both in the original cost of producing the parts, since one less part is required than formerly, and also the cost of 10 assembling and handling the parts is less than the old form of construction of battery cup and separate anvil. The double vent in the bottom of the battery cup is also an improvement over the central vent necessitated by the ordinary form of battery primer in which it was necessary to provide means for securing the base of the anvil at the bottom 15 of the battery cup.

25 In order that the invention might be fully understood, the details of an embodiment thereof have been thus specifically described; but

What I claim is:

30 1. In a shell, a battery primer embodying a primer cup and a battery cup, the said battery cup having bottom portions thereof forced into the interior thereof to constitute an anvil with a pointed apex and angular 35 supporting sides.

2. In a shell a battery primer embodying a primer cup, and a battery cup, the said battery cup having its bottom forced into the interior thereof to form a pointed anvil with the base thereof extending across 40 the cup, and having portions of the said inwardly projecting bottom cut away to provide double vents.

3. In a shell a battery primer embodying 45 a primer cup, and a battery cup, the said battery cup having its bottom forced into the interior of the cup to form a pointed anvil, and having a portion of the said bottom cut away to provide a vent, the base of the 50 anvil extending transversely of the cup.

4. In a shell a battery primer embodying a primer cup, and a battery cup adapted to receive the primer cup, and having its bottom forced into the interior thereof to provide 55 an anvil extending across the cup and adapted to enter the interior of the primer cup.

5. In a shell a battery primer embodying a primer cup and a battery cup, and an anvil formed integrally therewith and extending across the bottom of the cup to form a convenient opening in the bottom on each side of the anvil.

6. In a shell having a base with an aperture

ture through it, a battery cup primer comprising a primer cup, a battery cup having an anvil formed integrally therewith, and an inclosing hood with such hood placed in the aperture of the base and having its forward edge reamed outward, turned back and 70 firmly compressed in the base.

7. In a shell having a base provided with a reinforcing wound wad with an aperture through it, and a battery cup primer comprising a primer cup, a battery cup having an anvil formed upwardly from the bottom of said battery cup, and an inclosing hood, the said hood passing through the reinforcing wound wad and having its forward edge firmly upset into said wad.

8. In a shotgun shell including a paper tube and a cup of ductile material, an interior wad or reinforcement having an opening therethrough, in combination with a battery cup primer comprising a primer cup and a battery cup, there being an anvil formed integrally with said battery cup, and an imperforate hood inclosing the said battery cup primer at one end, and having its other end crimped into gas tight connection with the said interior wad or reinforcement.

9. In a central fire shotgun shell for nitro powders, the combination with a paper tube joined to a base of ductile material perforated at its center, having the edge surrounding said perforation depressed, in combination with a battery primer embodying a primer cup and a battery cup, the said battery cup having an anvil formed integrally therewith, and a flaring hood inclosing the outer end and sides of said battery primer and itself supported on the depressed edge surrounding the perforated center of the base and having its other end crimped or upset into gas tight connection with the base of the shell.

10. In a shotgun shell, the combination with a paper tube joined to a base of ductile material perforated at its center, having the edge surrounding said perforation depressed, of a battery primer embodying a primer cup and a battery cup, the said battery cup having an anvil formed integrally therewith, and a flaring hood inclosing the outer end and sides of said battery primer and itself supported on the depressed edge surrounding the perforated center of the base and having its other end crimped or upset into gas tight connection with the base of the shell, there being a flange formed around the bottom of the said flaring hood adapted to coöperate with the depressed edge surrounding the perforated center of the base.

11. The combination in a shell or battery primer embodying a primer cup, of a battery cup having portions of its bottom folded up into its interior into angular re-

lation so that they join to form an anvil which has an apex and inclined supporting sides.

12. The combination in a shell or battery primer embodying a primer cup, of a battery cup having a strip of material integral therewith extended upwardly and within the cup to a point or apex in proper relation to form an anvil.

10 13. The combination in a shell or battery primer embodying a primer cup, of a battery cup having a strip of its material extended upwardly into the interior of such cup to a point or apex in position to form an 15 anvil and provided with apertures on each side of such apex.

14. The combination in a shell or battery primer embodying a primer cup, of a battery cup having a narrow strip of its material extended upwardly from its bottom into the interior of the cup to form a point or apex in position to act as an anvil and cut away at each side of such apex to provide openings therethrough.

25 15. In a shell or battery primer, the combination of a primer cup, a battery cup, and an anvil formed integrally with the battery cup by having the bottom thereof formed to project into its interior whereby the center 30 of the projecting bottom comprises the point or apex of the anvil and being supported by an integral bridge of material spanning the bottom edge of the battery cup.

16. In a shell or battery primer, the combination of a primer cup, a battery cup, and an anvil formed integrally with the battery cup by having the bottom thereof formed to project into its interior whereby the center of the projecting bottom comprises the point 40 or apex of the anvil and being supported by an integral bridge of material spanning the bottom edge of the battery cup between diametrically opposed points therein.

45 17. In a shell or battery primer, the combination of a primer cup, a battery cup, and an anvil formed integrally with the battery cup by having the bottom thereof formed to project into its interior whereby the center of the projecting bottom comprises the point 50 or apex of the anvil and being supported by an integral bridge of material spanning the

bottom edge of the battery cup, there being a portion of the said inwardly projecting bottom remote from the point or apex of the anvil cut away to provide a vent.

55

18. In a shell or battery primer, the combination of a primer cup, a battery cup, and an anvil formed integrally with the battery cup by having the bottom thereof formed to project into its interior whereby the center 60 of the projecting bottom comprises the point or apex of the anvil and being supported by an integral bridge of material spanning the bottom edge of the battery cup, there being portions of the said inwardly projecting bottom remote from the point or apex of the anvil cut away to provide vents on two diametrically opposed sides of the point or apex of the anvil.

65

19. In a shell or battery primer, the combination of a primer cup, a battery cup, an anvil formed integrally with the said battery cup by having the bottom thereof formed to project into its interior whereby the center 70 of the projecting bottom comprises the point or apex of the anvil and being supported by an integral bridge of material spanning the bottom edges of the battery cup, and a hood inclosing the battery cup primer at one end.

75

20. In a shell or battery primer, the combination of a primer cup, a battery cup, an anvil formed integrally with the said battery cup by having the bottom thereof formed to project into its interior whereby the center 80 of the projecting bottom comprises the point or apex of the anvil and being supported by an integral bridge of material spanning the bottom edges of the battery cup, there being a portion of said inwardly projecting bottom remote from the point or apex of the 90 anvil cut away to provide a vent, and a hood inclosing the battery cup primer at one end.

85

In testimony whereof I have signed my name to this specification, in the presence of 95 subscribing witnesses, on this 19th day of August A. D. 1907.

GEORGE AUGUST MUENZENMAIER.
